CLAIM

The ornamental design for a flat hair clip, as shown and described.

DESCRIPTION

More than one reissue application has been filed for the reissue of U.S. Design Pat. No. D1,031,161. The reissue applications are application No. 29/989,558; and application Nos. 29/989,569 and 29/989,577 (the present application), both of which are divisional reissues of U.S. Design Pat. No. D1,031,161.

The present application is a reissue of U.S. Design Pat. No. D1,031,161, issued on Jun. 11, 2024, the entire disclosure of which is expressly incorporated herein by reference.

[FIG. 1 is a perspective view of a first embodiment of a flat hair clip according to the present design.]

[FIG. 2 is a front elevation view thereof.]

[FIG. 4 is a left side elevation view thereof.]

[FIG. 6 is a top view thereof.]

[FIG. 8 is a perspective view of a second embodiment of a flat hair clip according to the present design.]

[FIG. 9 is a front elevation view thereof.]

[FIG. 10 is a rear elevation view thereof.]

[FIG. 11 is a left side elevation view thereof.]

[FIG. 12 is a right side elevation view thereof.]

[FIG. 13 is a top view thereof.]

[FIG. 15 is a perspective view of [a third embodiment of] a hair clip [with open sides] according to the present design.

FIG. 16 is a front elevation view thereof.

FIG. 17 is a rear elevation view thereof.

FIG. 18 is a left side elevation view thereof.

FIG. 19 is a right side elevation view thereof.

FIG. 20 is a top view thereof; and,

FIG. 21 is a bottom view thereof.

The broken lines in the drawings depict portions of the flat hair clip that form no part of the claimed design.
